US00D586602S

(12) **United States Design Patent**
Sankey et al.

(10) **Patent No.:** **US D586,602 S**
(45) **Date of Patent:** **** Feb. 17, 2009**

(54) **LOW PROFILE DISC STORAGE CONTAINER**

(75) Inventors: **James K. Sankey**, Hudson, OH (US);
Ronald M. Marsilio, Mogadore, OH (US); **James N. Peterson**, North Canton, OH (US)

(73) Assignee: **Nexpak Corporation**, Duluth, GA (US)

(**) Term: **14 Years**

(21) Appl. No.: **29/305,346**

(22) Filed: **Mar. 18, 2008**

Related U.S. Application Data

(62) Division of application No. 29/235,348, filed on Jul. 29, 2005, now Pat. No. Des. 567,564, which is a division of application No. 29/161,658, filed on May 31, 2002, now Pat. No. Des. 508,813.

(57) **CLAIM**

The ornamental design for a low profile disc storage container, as shown and described.

DESCRIPTION

FIG. 1 is a perspective view of a low profile disc storage container showing our new design;

FIG. 2 is top plan view thereof, the bottom being a mirror image;

FIG. 3 is a front elevational view thereof;

FIG. 4 is a right side elevational view thereof, the left side being a mirror image; and,

FIG. 5 is a rear elevational view thereof.
